UNITED STATES PATENT OFFICE

165,219

COMBINED CARD BOX AND FOLDING
CANASTA TRAY OR SIMILAR ARTICLE

Charles F. Degner, Boonville, Mo.

Application January 20, 1951, Serial No. 13,898

Term of patent 14 years

(Cl. D34—13)

To all whom it may concern:

Be it known that I, Charles F. Degner, a citizen of the United States, residing at Boonville, county of Cooper, State of Missouri, have invented a new, original, and ornamental Design for a Combined Card Box and Folding Canasta Tray or Similar Article, of which the following is a specification, reference being made to the accompanying drawings, forming a part hereof.

In the drawings:

Fig. 1 is a plan view of a combined card box and folding canasta tray, showing my new design in opened position;

Fig. 2 is an end elevational view thereof in opened position;

Fig. 3 is a plan view of the top of the box in closed position;

Fig. 4 is a front elevation view of the box in closed position;

Fig. 5 is an end elevation view of the box in closed position, looking at the right end in Fig. 4;

Fig. 6 is an end elevational view of the box in closed position looking at the left end in Fig. 4;

Fig. 7 is a rear elevational view of the box in closed position, looking at the back in Fig. 4; and

Fig. 8 is a front elevational view thereof in opened position, looking at the right end in Fig. 2.

The dominant features of my new design are shown in solid lines in the drawing.

I claim:

The ornamental design for a combined card box and folding canasta tray or similar article, as shown and described.

CHARLES F. DEGNER.
